UNITED STATES PATENT OFFICE.

CHARLES SAW, OF PHILADELPHIA, PENNSYLVANIA.

APPARATUS FOR CARBONATING AND BOTTLING MALT LIQUIDS.

SPECIFICATION forming part of Letters Patent No. 601,735, dated April 5, 1898.

Application filed January 22, 1897. Serial No. 620,188. (No model.)

To all whom it may concern:

Be it known that I, CHARLES SAW, a citizen of the United States, residing at the city of Philadelphia, in the county of Philadelphia and State of Pennsylvania, have invented certain new and useful Improvements in Apparatus for Carbonating and Bottling Malt Liquors, of which the following is a specification.

My invention has relation to an apparatus for the carbonating and bottling of malt and similar liquids whereby foaming and loss of liquids are prevented and the operation is performed simply and quickly, and in such general connection it relates to the construction and arrangement of such an apparatus.

The principal objects of my invention are, first, to provide an apparatus for the carbonating and bottling of liquids wherein the liquid is first thoroughly mixed and agitated with the gas, after which the liquid is stilled by screening and then forced under pressure into the bottle, wherein the air has been first exhausted and in which a constant pressure of gas is uniformly maintained; second, to provide, in an apparatus for carbonating and bottling malt liquids, a carbonator consisting of a shell or drum divided longitudinally by a transverse partition into two compartments, the one portion of the partition being perforated to permit the liquid to flow from one compartment into the other; third, to provide in such an apparatus, in connection with the carbonator, a bottling-table and its nozzle, a delivery-pipe leading from that portion of the carbonator wherein the screened liquid is contained to the nozzle and terminating within the nozzle in a conical screen or rose adapted to direct the liquid against the walls of the nozzle, so that the liquid will be delivered to the bottle in a filmy condition; fourth, to provide in such an apparatus, in connection with the carbonator, the bottling-table, bottling-nozzle, and pipe connection between the carbonator and nozzle, and a reservoir connected with the nozzle and adapted to be filled with excess of gas from the bottle, whereby a constant and uniform pressure within the bottle may be maintained, and, fifth, to provide in such an apparatus a spring-controlled check-valve located in the delivery-pipe to the nozzle and a similar valve located in the pipe leading from the nozzle to the gas-

reservoir and a lever adapted to open either valve independently of the other.

My invention consists of an apparatus for carbonating and bottling malt liquids constructed and arranged in substantially the manner hereinafter described.

The nature, scope, and characteristic features of my invention will be more fully understood from the following description, taken in connection with the accompanying drawings, forming part hereof, in which—

Figure 1 is a side elevational view, partly sectioned, of a carbonating and bottling apparatus embodying main features of my invention. Fig. 2 is an enlarged longitudinal sectional view of a portion of the carbonator, showing the construction and arrangement of the chambers therein and of the partition therefor. Fig. 3 is a transverse sectional view of the carbonator looking toward the partitioned end. Fig. 4 is an enlarged side elevational view, partly sectioned, of the bottling-nozzle and of a bottle in operative position with respect thereto. Fig. 5 is a top or plan view of Fig. 4, partly sectioned; and Fig. 6 is a longitudinal section, enlarged, of the conical rose on the end of the delivery-pipe.

Referring to the drawings, A represents the pump, of ordinary construction, with the beer-pipe a and gas-pipe a' entering at one end thereof and the discharge-pipe a'' delivering the mixed liquid and gas from the other end. The pipe a'' discharges from the pump A into one end of a carbonator B. The longitudinal center of this carbonator is traversed by a shaft b , one end of which is provided with agitating-blades b' . The shaft b is journaled, as at b^2 , in the ends of the carbonator and is adapted to be revolved by pulleys b^3 , connected with a power-shaft by suitable means. (Not shown.) The carbonator B by preference is made in two parts suitably united together—by preference with bolts b^4 . Within the carbonator and at that end opposite to that in which the pipe a'' enters is arranged a partition d , which divides the carbonator B into two chambers d' and d'' , in only one of which, d' , the mixed liquid and gas enter through pipe a'' and in which the mixture is agitated by the blades b' of the shaft b . The partition d by preference is arranged obliquely in the carbonator, as shown in Figs. 1 and 2,

and its upper half is perforated, as at d^3 , to permit the liquid in chamber d' to percolate through the partition and to fall along the partition until it reaches the bottom of the chamber d^2 , as shown in Fig. 2. By this arrangement the liquid, which is in a foamy condition in the chamber d' , is strained and enters the chamber d^2 in a still or substantially quiet condition. From the bottom of the chamber d^2 of the carbonator a pipe e leads to the nozzle D of the bottling-table E. This pipe e extends upward into the carbonator to prevent the drawing off of sediment, &c., and the pipe e enters the nozzle D in substantially a horizontal position.

Referring now to Fig. 4, the nozzle D consists, essentially, of the parts hereinafter described. The nozzle consists of a vertically-arranged tube or sleeve f , the upper end of which is conical, as at f' , and adapted to receive a cork f^2 . The lower end of this sleeve f is enlarged to receive an elastic cushion or washer f^3 , which is secured to the sleeve by a ring f^4 . This cushion f^3 is bell-shaped or flaring at its lower end and is adapted to fit tightly down upon the mouth of the bottle f^5 , which is supported upon the bottling-table E. The nozzle D and its tube f are adapted to be moved toward or away from the table E in the ordinary manner by means of the treadle E', which operates, through the frame E² and cross-bar E³, a cross-bar E⁴, within which the nozzle D is supported, as shown in Fig. 1. Preferably at right angles to the tube f is a second tube or stud g , communicating with the interior of the tube f by means of the downwardly-projecting opening or port g' . In the open end of this tube g is placed a conical-shaped rose or strainer-cap h , as illustrated in Fig. 6, the perforations in which are arranged so that liquid entering the cap h is directed toward or against the inner wall of the tube g , as indicated by the arrows in Figs. 4 and 6. This cap is fitted on the end of the pipe e , leading from the carbonator B, which pipe is secured to the tube g by means of the screw-ring g^2 , substantially as shown in Fig. 4. The pipe e is provided near the tube g with a check-valve h' , the stem h^2 of which is preferably under the tension of a spring h^3 , serving normally to close the valve h' upon its seat, as clearly shown in Fig. 5. From the tube f and at the connection of the tube g therewith is formed a second tube k , having an upwardly-projecting opening or port k' , entering the tube f above the port g' of the tube g . From the tube k extends a pipe m , having a check-valve m' , whose stem m^2 is surrounded by a spring m^3 , which holds the valve upon its seat in a manner similar to that of the valve h' and as indicated in Fig. 5. The stems h^2 and m^2 of valves h' and m' project toward each other, and between the stems is arranged a lever n , pivoted, as at n' , to the tube f and having at its free end a handle n^2 . When the lever n is moved toward the valve h' , it acts against the stem h^2 and

opens the valve h' against the influence of a spring h^3 . When the lever is moved toward the valve m' , it serves to open said valve by depressing the stem m^2 against the tension of the spring m^3 . The pipe m enters or discharges into a reservoir o, the lower end of which is provided with a safety-valve o' and also with a pipe o², leading to a keg or other suitable receptacle o³. On the reservoir o is also placed the pressure-gage o⁴, by means of which the operator may ascertain the pressure of gas within said reservoir. The carbonator B is also provided with a pressure-gage B' and sight-glass B³, as illustrated in Fig. 1, and it has also a pipe B², whereby carbonic-acid gas may be introduced directly into the carbonator.

The cork f^2 , which is first introduced into the conical end f' of the tube f , is forced downward from said end through the tube and into the mouth of the bottle f^5 by a plunger p , carried by the frame p', operated by a handle or lever p^2 in the ordinary and well-known way. By making the end f' of the tube conical any moisture on or in the cork f^2 is forced outward away from the tube f during the passage of the cork into the straight portion of said tube. In this arrangement no water can enter the bottle f^5 .

The operation of the apparatus is as follows: A mixture of the liquid and carbonic-acid gas is pumped into the carbonator B, in the chamber d' in which it is further mixed by the agitators or paddles b'. The liquid rises in the chamber d' until it reaches the perforations d^3 of the partition d , through which it percolates and flows downward on the partition into the chamber d^2 . In this chamber the liquid, though mixed with gas, is still and has hardly any perceptible "head" or "bead." The stilled liquid is now drawn off into the pipe e . When the first bottle is to be filled, or rather if the reservoir o contains no carbonic-acid gas, the bottle is placed on the table, the nozzle D is lowered by the treadle E', and the valve h' in pipe e is opened by the lever-arm n . The liquid from the chamber d^2 is then forced into the bottle, it being directed against the walls of tube g and of tube f and against the walls of the bottle f^5 , as indicated in Fig. 4. The bottle will be first half-filled, and then the operator by moving the lever-arm n in the other direction permits the valve h' to close and at the same time opens the valve m' , controlling the outlet of gas and air from the nozzle D into the reservoir o. When this has been done, the lever n is moved in a reverse direction. The valve m' is thereby closed and the valve h' opened to permit the liquid to again enter and to fill the bottle f^5 . When the bottle is filled, the lever-arm n is moved to a position where neither valve-stem h^2 or m^2 is operated, and both valves h' and m' are closed. The plunger p is now depressed and the cork forced into the bottle. When the next bottle is to be filled, the nozzle D is depressed by the

treadle E' and the valve m' is first opened by the lever-arm n and held open until the bottle is filled with carbonic-acid gas, which, being heavier than air, drives the air out into tube f, from which it may escape by slightly easing up the treadle E' to permit the springs E⁵ to lift the nozzle D slightly from the mouth of the bottle and then again depressing the nozzle D down upon the bottle. The bottle is filled with carbonic-acid gas from the reservoir o, but not under pressure. The valve h' is now opened and kept open until the bottle is filled, the surplus gas being allowed to escape into the reservoir o by again opening the valve m' after valve h' is closed. Should there be an excess of pressure in reservoir o, the safety-valve o' will permit the excess to escape into the open air, and if any of the liquid is forced up into the reservoir o it will drain into a keg or other receptacle o³, from which it may be emptied into the carbonator through the pump A without deterioration. By means of this apparatus each bottle may be filled without the foaming of the liquid, and each bottle is kept under uniform pressure of gas by means of the reservoir o.

The conical rose h serves to screen and to thereby still the liquid before it enters the tube f, and it also serves, in connection with the direction of the port g', to direct the liquid in a film upon the walls of the tube f and the walls of the bottle f⁵.

By arranging the gas-port k' above the liquid-port g' the escape of liquid from the pipe e into the reservoir is prevented, and air or gas from the bottle may escape into the tube f above the liquid-port and be drawn off without obstructing the flow of the liquid.

Having thus described the nature and objects of my invention, what I claim as new, and desire to secure by Letters Patent, is—

1. In an apparatus of the character described, a carbonator, divided into two cham-

bers by a transversely and obliquely arranged partition, the upper portion of said partition being perforated to permit of the flow of liquid from one chamber to the other without foaming, substantially as and for the purposes described. 45

2. In an apparatus of the character described, a carbonator, a shaft traversing the same, agitating blades or paddles secured to one portion of said shaft, and an obliquely arranged partition dividing said carbonator into two chambers in only one of which the paddles are adapted to rotate, said partition having its upper portion perforated to permit of the passage of liquid from the agitating-chamber to the other chamber without foaming, substantially as and for the purposes described. 50

3. In an apparatus of the character described, a carbonator, a bottling-table and a nozzle, a delivery-pipe leading from the carbonator to the nozzle and terminating in the nozzle in a conical screen or rose adapted to direct the liquid against the walls of the nozzle, substantially as and for the purposes described. 65

4. In an apparatus of the character described, a carbonator divided into two chambers by a partition, the upper portion whereof is perforated to permit of the flow of liquid from one chamber to the other, a delivery-pipe leading from the latter chamber, a bottling-nozzle, and a conical rose located within the nozzle and connected with said delivery-pipe, substantially as and for the purposes described. 75

In testimony whereof I have hereunto set my signature in the presence of two subscribing witnesses.
